E. WESTON

TELEPHONE PLUG CONNECTER

Filed Dec. 19, 1923

Inventor:

Edward Weston,

By Raymond M. Brickenstein,

Attorneys.

UNITED STATES PATENT OFFICE.

EDWARD WESTON, OF NEWARK, NEW JERSEY, ASSIGNOR TO WESTON ELECTRICAL INSTRUMENT CORPORATION, OF NEWARK, NEW JERSEY, A CORPORATION OF NEW JERSEY.

DESIGN FOR A TELEPHONE-PLUG CONNECTER.

Application filed December 19, 1923. Serial No. 8,099. Term of patent 14 years.

To all whom it may concern:

Be it known that I, EDWARD WESTON, a citizen of the United States, residing at Newark, in the county of Essex and State of New Jersey, have invented a new, original, and ornamental Design for Telephone-Plug Connecters, of which the following is a specification, reference being had to the

accompanying drawing, forming part thereof, and wherein the single figure is a perspective view of the plug connecter.

I claim:

The ornamental design for a telephone plug connecter, as shown.

EDWARD WESTON.
